US0D1025515S

(12) **United States Design Patent** (10) **Patent No.:** **US D1,025,515 S**
(45) **Date of Patent:** **** Apr. 30, 2024**

(54) **ANTI-CAT STING PAD**

(71) Applicant: **Yincong Xiao**, Putian Fujian (CN)

(72) Inventor: **Yincong Xiao**, Putian Fujian (CN)

(**) Term: **15 Years**

(21) Appl. No.: **29/908,834**

(22) Filed: **Jan. 16, 2024**

(51) **LOC (14) Cl.** **30-99**

(52) **U.S. Cl.**

USPC **D30/199**; D30/119
